GARMENT FOLDING APPARATUS

James W. Steele, North Kansas City, Mo.

Application August 7, 1950, Serial No. 178,041

6 Claims. (Cl. 223—37)

1

The present invention relates to garment folding devices, and aims to provide an improved folding apparatus which is adapted for convenient operation as well as more efficient and wider range of garment folding action, such as to include the proper folding operation as required for not only the various types of men's shirts but also the common forms of pajamas, sweaters, light weight coats and jackets and similar men's garments requiring a folding treatment in connection with packaging operations, or the like.

It is a special object of the invention to devise folding apparatus which is adapted to produce a fold in garments of the type indicated and in which the operation consists in making what may be termed short and wide folds in the garment in lieu of the so-called long and narrow type of fold, as in the conventional style of men's shirts. In this connection it is also an object of the improvements to provide a folding construction adapted to the use of either single or double cardboards or stiffening inserts between the garment folds, and resulting in an efficiently folded and reinforced garment for packaging purposes in either case.

In its preferred form the invention comprises a construction providing a table or supporting surface especially adapted for the garment folding operation, together with a special form of hinge leaf member movable into and out of operative or working relation to the table surface, and said hinge leaf in turn carrying an assembly of pivotal arm elements also movable with said leaf toward and away from the table surface besides being mounted in slidable relation to the leaf for the further positioning of said arms in the desired operative or garment folding relation to the top or working face of the table.

The invention further seeks to provide a construction of the character indicated in which the necessary folding operation is adapted to be carried out and including the application of the usual band elements, if desired, in practically the same operative or working interval for either regular or standard shirts or for sport shirts, pajamas, and the like.

With the foregoing general objects in view, the invention will now be described in detail by reference to the accompanying drawings illustrating one form of construction which I have found to be practical and efficient for the accomplishment of the desired purposes as above indicated—after which the various improved features and combinations thereof deemed to be novel and patentable will be particularly set forth and claimed.

2

In the drawings—

Figure 1 is a perspective view illustrating a garment folding apparatus constructed in accordance with the present invention;

5 Figure 2 is a similar view (on a slightly larger scale) showing the upper portion of said apparatus with the folding leaf member in lowered position and the pivoted arm assembly carried thereby shifted forward into operative relation to a sports garment shown as applied in initial folding relation to the apparatus;

10 Figures 3, 4, 5 and 6 are also perspective views illustrating successive steps in the shirt-folding operation, up to its completely folded and banded state as represented in Figure 6;

15 Figure 7 is a side perspective view illustrating the initial stage of operation as required for folding a pajamas suit form of garment; and

20 Figures 8 and 9 are similar views representing succeeding steps in the folding operation initiated by the stage illustrated in Figure 7.

25 In the cycle of laundry practice, as it seems to prevail at the present time, there is a definite trend to what may be termed short and wide folds in the packaging of the finished garment, particularly as to men's shirts, doubtless influenced by the popularity of sport shirts, which lend themselves more naturally to the wider folded state. While shirt folding machines have 30 been designed to perform the usual types of shirt-folding operations, they have not been adapted to provide for anything but the common or standard so-called long and narrow folds, as represented by the orthodox form of finished shirt. Consequently the variations from these dimensions in the length and width of shirt folds have been for the most part dependent upon the particular ability and skill of the operator, thus in no way insuring any accuracy or uniformity in 35 the fold lines and dimensions of the finished-folded product—always an important factor and desideratum in connection with garment finishing operations prior to the packaging of the same.

40 It is therefore a primary object of the present invention to provide improved garment folding apparatus adapted to fulfill all the requirements as regards these changing fold designs and in addition to the requirements of the previously prevailing practice; and also to provide a construction answering all the other requirements relating to the use of cardboard or stiffening material as well as the securing or banding of the finished-folded product.

45 Referring now to the accompanying drawings in detail, and more particularly to Figure 1, this view shows a complete machine or apparatus of

the present improved type, comprising a conventional form of body or upright framework 12 supporting a top or table portion 14 providing a working surface for the garment-folding operation. The interior of said body or framework 12, beneath its top or work-table portion, serves as a storage compartment 16 for supplies of material used in the folding operation, which may be stored therein on an interior shelf 18, open to the front of the machine.

The top surface or working face of the table 14 is specially constructed for the laying of the shirt 20 thereon in fully spread relation, with the front of the shirt facing downward (see Figure 2). The table is accordingly formed with a shallow collar well or depression 22 for receiving the collar portion of the shirt when positioned for folding; and from this depression 22 also extends a dado type of groove 24 to the front edge of the table for the purpose of accommodating the button and buttonhole pleats of the shirt while in this shirt folding position—see Figures 5 and 6. From this it will be seen that the location of the collar within said depression 22 and the extension of the shirt button and buttonhole pleats along said groove 24 serves to definitely align the shirt in true and accurate position on the table for the carrying out of the successive steps of the folding operation, as hereinafter explained. There is also provided a set of friction strips or pads 26 and 26' of soft gripping material, such as rubber or felt, located in spaced relation transversely of the table top and serving as means for preventing any casual slipping of the garment during the folding process. Intermediate the inner strips 26 and the outer strips or pads 26' are provided recesses 28 forming receptacles extending from front to rear of the table for the storage of shirt bands 30 at a level below that of the top surface of the table, i. e., in position for facilitating the lifting of said bands 30 for applying the same at both ends of the folded shirt—as represented in Figure 6. The outer margins of the recesses or receptacles 28 are provided with scalloped notches or openings 32 designed to enable the operator to make convenient finger engagement with the side edges of said bands for separating the same.

The upper working face of the table 14 is still further provided with spaced parallel guide strips 34, the distance between which corresponds to the width of the pattern according to which the shirt is to be folded (compare Figures 3 to 6). The front margin of the table is also formed with an upright ledge 36 adapted to define the first transverse fold line of the garment and also properly confine the garment in its initial folding position.

An important feature of the invention resides in an improved form of hinged leaf member 40 carrying an assembly of folding and guide arms especially constructed and designed for cooperation with the described form of table top surface in producing the required folding operation. This hinged leaf and arm assembly comprises a metal leaf member 40 hingedly mounted by means of a transversely extending hinge structure 42 at the rear of the table top 14, the width of said member 40 corresponding to the space between the recesses or receptacles 28 for the bands 30, and the length of said member 40 being such as to extend (when in lowered or working position) to the forward ends of the friction strips or pads 26, which latter serve incidentally as bumper pads for cushioning said leaf member

when dropped into operative position upon the table top. Mounted for sliding movement upon the upper face of said leaf member 40 is a transverse plate 44 provided with a finger-engaging knob 46, the stem of which is connected with a guide element 48 mounted slidably in a slot 50 extending from the hinge structure 42 along the middle line of the leaf member 40 and approximately half its length. The transverse plate 46 serves as an adjustable support for the folding and guide arms, all of substantially the same length and comprising two folding arms 52 formed with inwardly projecting hinge ends 53 mounted in bearing elements 54 so arranged that said arms 52 swing into and out of positions adjacent to the side edges of the leaf member 40; whereas the other arms 56 (also of approximately the same length as the arms 52) have inturned shank extensions 58 terminating in hinge ends 60 for mounting in bearing elements 54' at right angles to the hinge ends 53 of the folding arms 52, whereby said arms 56 are adapted to be swung outwardly into their operative position extending alongside the outer margins of the slots or receptacles 28 for the bands 30. The hinge ends of the various arms are all fitted with detachable cotter pins 62, thus adapting the arms for easy assembly and replacement at any time.

When the hinge leaf member 40 and the parts carried thereby are swung backward, into inoperative position, it encounters an upright extension plate 64 carried by the rear margin of the table 14 and serving as a backstop or bumper for said leaf member 40. The upper portion of said extension plate 64 is also constructed to provide a rack member 66 designed to carry a supply of shirt reinforcing or stiffening cardboards 68 of the desired size, as shown.

It will therefore be seen that I have provided a construction which is designed to properly position the garment for the folding operation and thereafter retain the garment in this correctly aligned position for the remaining steps of the folding process, for which steps the invention provides a unitary assembly of hinge leaf member equipped with folding and guide arms serving to facilitate the folding operation in an efficient manner as regards producing accurately folded garments, all uniformly conforming to substantially the same size as to their folded state at the end of said process.

The drawings illustrate this process as carried out in the folding of a sport type of shirt 20, which is applied to the top or working face of the table, with the front of the shirt facing downwardly to locate its collar portion within the collar well or depression 22 and its button and buttonhole pleats aligned with the dado groove or slot 24, and the body portion of the shirt draped over the front of the apparatus, or hanging over the ledge portion 36, as illustrated in Figure 2. As the placing of the garment in this position also causes it to rest upon the friction pads or strips 26 and 26', this insures against any casual displacement of the garment away from this correctly aligned position while undergoing the remaining steps of the process.

Following the laying of the shirt in the position illustrated in Figure 2, the hinge leaf member 40 carrying the pivoted arm assembly is swung down on to the upper portion of the garment (as represented in said view), which operation also brings the two outer arms 56 down alongside the outer margins of the band slots or recesses 28, while the other pivoted arms 52 re-

main slidingly supported by the upright panel 64. The operator now places one of the cardboard inserts 68 upon that portion of the shirt extending between the guide strips 34, which insertion is accurately guided by the location of said guide strips and the front table edge 36, so that the rear edge of the cardboard is located in proper alinement with the forward edge of the hinge leaf member 40, as represented in said Figure 2.

The operator next proceeds to fold the left sleeve of the shirt by drawing it across the table to the right against the pull of the left guide arm 56, then lowering the right fold arm 52 upon the sleeve and drawing the latter back to the left around said fold arm 52 so that the cuff and gusset portions of the sleeve come to rest upon the cardboard in the position shown in Figure 3—said cuff portion being located between the forward edge of the leaf member 40 and the front ledge 36 of the table.

In the same manner the operator folds the right sleeve by first drawing it across the table to the left against the pull of the right guide arm 56 and thereafter lowering the left fold arm 52 upon the sleeve and drawing the latter to the right around said fold arm so that the cuff and gusset portions of the right sleeve come to rest on top of the folded left sleeve, as represented in Figure 4. After this folding of each sleeve, the extra fullness in the shirt body at each side thereof is folded over inwardly so that the width between the outer edges of said inturned portions is the same as that of the upper folded shoulder portion of the shirt.

In the event that it should be desired to use two of the cardboard inserts 68 in place of only one, in the folding operation, the extra cardboard 68 is inserted in somewhatlapping relation to the other board and underneath the hinge leaf member 40, prior to the folding of the sleeves as above described, the rear edge of the extra cardboard being located in approximate alinement with the shoulder line of the garment—as indicated in Figure 4.

The operator next catches up the lower tail portion of the shirt and snugly folds it up on to the shoulder portion, tucking in any excess length of the tail portion, so that the rear fold line of said tail portion will come in line with and match the shoulder line of the garment, as indicated in Figure 5.

The operator then grasps the knob 46 and pushes the sliding plate 42 and the arm assembly carried thereby back to the rear of the table, and proceeds to make the final fold of the shirt and its cardboard insert (or inserts) by doubling the same over on to the lower portion of the leaf member 40 and into the compact folded form represented in Figure 6. With the shirt in this final folded state, one of the bands 30 is applied to and secured around each side of the folded shirt, thus completing both the folding and banding operation, when the garment may be readily removed by slightly lifting both the shirt and leaf member to clear the shirt from engagement with the pad elements 25. At the same time the operator swings said leaf member and arm assembly back into their original position, as illustrated in Figure 1.

Besides being primarily adapted for the folding of shirts in the manner above outlined, the apparatus is also equally well designed for the folding of other types of sport garments, such as pajama suits, light weight jackets, sweaters and

coats, with the same facility and precision, and all to the same size and pattern of fold. In Figures 7 to 9 is illustrated such adaptation of the apparatus for carrying out said folding operation in connection with a two-piece pajama suit.

Starting with the metal leaf member 40 and its hinged arm assembly in their raised position, as represented in Figure 7, the operator places the pajama jacket 21 face down upon the working face of the table in exactly the same manner as in starting the shirt folding operation already explained, after which the pajama pants 23 are laid crosswise over said jacket 21, with the front or fly portion of the pants toward the front of the table and the opposite portion thereof alined with the top of the jacket collar. The operator then proceeds with the same steps of the folding operation as in the case of shirt folding, to wit, first bringing the hinge leaf member 40 with the guide arms 56 into lowered position, then bringing the left sleeve and top of the pants first around over the left guide arm 56 and then back in a reverse direction around the right fold arm 52 (after swinging the latter into lowered position); then following the same operation as to the right sleeve and leg portions of the pants, using the right guide arm 56 and the left fold arm 52, and meanwhile folding inward the extra fullness at the sides of the jacket to produce straight fold lines in proper alinement with the sides of the shoulder portion thereof—as illustrated in Figure 8. The operation is then completed by substantially the same steps as followed in the shirt folding process, i. e., by catching up the lower tail portion of the jacket 21 and folding it up on to the shoulder and pants portions while tucking in any excess length of the jacket so that its rear fold line will fall in line with and match the shoulder line—after which the operator pushes the sliding plate 42 and arm assembly back to the rear of the table, as indicated in Figure 9. The folded garments may then be banded (if desired) and thereafter removed as in the case of the single folded shirt in the manner already described. Card inserts 68 may or may not be used, as preferred—and in any event a neatly folded product is obtained in substantially the same time as required for the folding of a shirt and having all the same advantages as to compactness and uniform folding to the same size; in addition, the process affords ample opportunity to check the garment pieces to assure that the same are matched properly in pairs, at the very start of the operation.

From the foregoing it will therefore be apparent that I have devised a practical and comparatively very simple construction for the carrying out of the purposes of the invention as herein stated; and while I have shown and described what I now regard as one of the preferred forms of construction for embodying the aforesaid improvements, I nevertheless desire to be understood as expressly reserving the right to make whatever changes or modifications may fairly be deemed to fall within the spirit and scope of my invention as defined by the appended claims.

What I claim is:

1. Garment folding apparatus comprising, in combination, a table having its top working face provided with a collar recess and a dado slot or groove extending from said recess, a leaf member carrying a folding arm assembly and pivotally mounted on the table top for movement into and out of position in operative relation to said working face of the table and resilient pads on said

table top in position for serving as cushioning means for said leaf members and also as friction means for retaining the garment against shifting movement on said working face of the table.

2. Garment folding apparatus comprising, in combination, a table provided with garment positioning means on its upper face, a leaf member pivotally supported by said table for movement into and out of operative relation to said upper face of the table, and a set of garment folding and guide arms pivotally mounted on said leaf member and also provided with a slidable connection therewith permitting adjusting movement of said arms toward and from the rear portion of the table.

3. Garment folding apparatus comprising, in combination, a table provided with garment positioning means on its upper working face, a leaf member pivotally supported by said table for movement into or out of operative relation to said working face of the table, and two pairs of folding and guide arms pivotally supported by opposite sides of said leaf member for swinging movement about axes at right angles to each other and movable with said leaf member into spaced parallel positions at said working face of the table.

4. Garment folding apparatus comprising, in combination, a table provided with garment positioning means on its upper working face, a leaf member pivotally supported by said table for movement into or out of operative relation to said working face of the table, and two sets of garment folding and guide arms provided with pivotal supporting means at opposite sides of said leaf member and movable therewith into spaced parallel positions at said working face of the table, said pivotal supporting means being slidably mounted on said leaf member for accommodating sliding movement of said folding and guide arms toward and from the rear portion of the table.

5. Garment folding apparatus comprising, in combination, a table provided with garment positioning means on its upper working face, a leaf member pivotally supported by said table for movement into or out of operative relation to said working face of the table, a plate member slidably secured to one face of said leaf member, and a set of garment folding and guide arms pivoted upon said plate member at opposite sides of the leaf member and adapted to be swung therewith into spaced parallel positions at the working face of the table, said pivoted arms being movable with said plate member toward and from the rear portion of the table.

6. Garment folding apparatus comprising, in combination, a table provided with garment positioning means on its upper working face and including a transverse retaining ledge at the front margin of the table, a pivotal leaf member movable into and out of operative position over said working face of the table for bringing the forward edge of said leaf, when in operative position, at a distance from said retaining ledge corresponding to one dimension of the fold to be produced in the garment, a set of garment folding and guide arms pivotally mounted on said leaf member, and guide strips at opposite front corners of the table at a distance apart corresponding to the width to which the garment is to be folded.
